UNITED STATES PATENT OFFICE.

OSCAR FISHER, OF PORT ANGELES, WASHINGTON.

FEED-WATER HEATER.

1,134,324.

Specification of Letters Patent. Patented Apr. 6, 1915.

Application filed December 11, 1913. Serial No. 806,086.

To all whom it may concern:

Be it known that I, OSCAR FISHER, a subject of the King of Great Britain, and residing at Port Angeles, Clallam county, State of Washington, have invented a new and useful Feed-Water Heater, of which the following is a specification.

My invention relates to feed water heaters.

One of the objects of my invention is to provide a simple and practical feed water heater which will be inexpensive to manufacture and efficient in use.

Another object is to provide a device of the above character having few parts which may be easily removed and replaced as desired or may be necessary.

Other objects will be in part obvious and in part hereinafter pointed out.

The invention accordingly consists of such features of construction, combination and arrangement of parts as will be hereinafter more specifically pointed out, and the scope of the application of which will be indicated in the following claims.

In the accompanying drawing, in which is shown one of various possible embodiments of the device, Figure 1 is a side elevation of the complete device; Figs. 2 and 3 are opposite end views; Figs. 4 and 6 are detail views of tube sheets; Fig. 5 is a longitudinal section of the device shown in Fig. 1 taken on the line 5, 5, Fig. 2, certain parts being omitted for the sake of clearness; Fig. 7 is a detail elevational view of a partition member; Fig. 8 is an end view of the tube sheet with the tubes in place; Fig. 9 is a detail elevational view of one of the parts.

Similar reference characters denote corresponding parts in the several views.

Referring now to the drawing in detail and more particularly to Fig. 5, a cylindrical casing H is provided at one end with a tube sheet K, secured to the flange J, and at its opposite end a copper expansion member E secured by flanges F and G, which is in turn provided with a similar sheet C secured to the flange D. Between these sheets extend a plurality of pipes Y through which water is adapted to circulate and be exposed to the heat of exhaust steam entering the casing or chamber H through pipes or ports R, S, T, U.

Adjacent each sheet C and K are separating members B and L to which are secured end plates A and M respectively by means of fastening bolts W and a main center tie

bolt X. The end wall A is provided with two openings to one of which is connected a pipe N for conveying the heated water to the boiler and to the other a pipe O connected with the feed pump. (Not shown.) The separating ring it will be noted, as shown more clearly in the detail view, is provided with a transverse partition which permits the cold water to enter and the hot water to leave the device from the same end, and positively causes the desired circulation past the exhaust entrance pipes in a substantially U-shaped path whereby the cold water is first subjected to entering hot steam.

The steam after passing over the heating pipes goes out through the nozzle I into the stack. Such steam as is condensed leaves through the pipe P, provided with a trap Q. A connection Z is adapted to connect these members. A drain V is provided at one end for drawing off the water, as when the engine is not running and there is danger of the water freezing.

It is thought the method of use and operation of the device is obvious and that a description thereof may be omitted. It is sufficient to state that the device is relatively small and compact and while particularly adapted for use with small engines, such as used for operating steam shovels and the like, it may be used in other relations if desired.

It is thus seen that this invention provides a simple and practical device adapted to accomplish among others all of the objects and advantages above set forth.

I am aware that considerable variation is possible in the details of construction herein shown and described, without departing from the spirit of my invention, and I do not intend to limit myself thereto, except as pointed out in the following claims, in which it is my intention to claim all the novelty inherent in the structure shown and described as broadly as the state of the art will permit.

Having thus described my invention what I claim as new and desire to secure by Letters Patent is:

1. In a feed water heater, in combination, a casing, an end wall member at the rear end of said casing, an expansion member connected at one end to said casing and forming a continuation thereof, a tube sheet at the rear end of said casing and located short of the end wall member to form a

chamber, a second tube sheet at one end of said expansion member, and an end wall member adjacent the said last mentioned tube sheet spaced apart therefrom and provided with pipe connections therethrough, a separating plate adjacent each of said tube sheets, the plate adjacent the tube sheet at the end of the expansion member being divided centrally to form upper and lower 10 water passages, circulating means connected with said tube sheets and provided with inlet and outlet openings, and steam inlets in the walls of said casing adapted to direct the flow of steam against that portion of 15 the circulating means conveying the incoming water to be heated.

2. In a feed water heater, in combination, a casing, an end wall member at the rear end of said casing, an expansion member 20 connected at one end to said casing and forming a continuation thereof, a tube sheet at the rear end of said casing and located short of the end wall member to form a

chamber, a second tube sheet at one end of said expansion member, and an end wall member adjacent said last mentioned tube sheet and provided with pipe connections therethrough, a separating plate adjacent each of said tube sheets, the plate adjacent the tube sheet at the end of the expansion member being divided centrally to form upper and lower water passages, circulating means connected with said tube sheets and provided with inlet and outlet openings, and steam inlets in the walls of said casing 30 adapted to direct the flow of steam against that portion of the circulating means conveying the incoming water to be heated, an outlet for the exhaust steam, trap means for permitting the withdrawal of the condensed steam, and means for draining the circulating means.

OSCAR FISHER.
